ELECTRICAL APPARATUS

Johannes Nathanael Hiensch and Eduard Maria Henricus Lips, Eindhoven, Netherlands, assignors to N. V. Phillips' Gloeilampenfabrieken, Eindhoven, Netherlands, a corporation of the Netherlands

Application August 4, 1939, Serial No. 288,351
In Germany September 2, 1938

1 Claim. (Cl. 173—324)

In copending application, Serial Number 210,803, filed May 28, 1938, there is described an electrical apparatus, for example, a radio-receiving set, in which the conductor system is produced by die-casting. Such a conductor system has among other things the advantage that the reproducibility is much greater than that of the usual conductor systems wherein the various conductors between the parts are constituted by loose wires, cables, etc. Besides, as compared with the usual conductor systems, the conductor system according to the above mentioned application is considerably more surveyable and has, in addition, a very rigid appearance.

The present invention relates to an improved process of producing such an apparatus. The process according to the invention is characterised in that the carrier plate or plates, on which the conductor system is to be arranged, is or are provided with apertures through which are passed the connecting wires or connecting strips of the parts to be secured to the conductor system, whereupon the conductor system is produced by means of the die-casting process and the parts are secured to the conductor system.

This process has various advantages. Before producing the conductor system by the die-casting process on the carrier plate, the various parts to be secured to the conductor system are mounted on the carrier plate. This carrier plate consequently serves as an assembly templet. Furthermore the conductor system is produced in a die-casting mould on the carrier plate. This mould therefore is only used during the time which is required for producing the conductor system, this in contradistinction with the process described in the previous application wherein the mould also is utilised as an assembly templet. According to the present invention, it is rendered possible with respect to the contents of the previous application, to obtain a greater production with the same number of available die-casting moulds.

In order to avoid that during die-casting of the conductor system the material used therefor leaks too high a degree between the walls of the apertures in the carrier plate and the connecting wires or connecting strips arranged in these openings, the walls of the apertures in the carrier plate surround the connecting leads passed through these apertures so tightly that in each aperture the distance between the wall of the aperture in the plate and the external side of the wire or strip passed through the opening is approximately at the most 0.2 mm.

- In the process according to the invention, the connecting wires or strips used for securing the various parts to the conductor system are constituted by the connecting leads of the parts.
- 5 The said connecting strips may be produced, for example, by punching and suitably bending the terminal leads of the various parts. As described in the previous application, the process according to the invention also permits of the various parts being secured to the conductor system during the die-casting operation. Due to the change in volume of the material of the conductors of the system when cooling down, this material may shrink for example, round the connecting wires or strips. It is alternatively possible that the material of the conductor system is alloyed with the material of the connecting wires, thus establishing the connection of the conductor system to the parts.
- 10 20 However, according to the invention it is also possible that, after the conductor system has been provided, the connections of the various parts to the conductor system are established by riveting, welding or soldering.
- 25 30 35 In the latter case use is preferably made of a solder which has a lower melting point than that of the material of the conductor system and of the connecting wires or strips. The material used for the carrier plate may be, for example, a kind of artificial resin. The conductor system may be constituted, for example, by lead or a lead alloy.
- The invention will be more clearly understood by reference to the attached drawings showing, 40 45 50 55 by way of example, some embodiments according thereto.
- Fig. 1 is a plan view of a portion of a carrier plate comprising the conductor system of a radio-receiver according to the invention. Figs. 2 and 3 are partial cross-sectional views taken respectively on lines II—II and III—III showing two possibilities of fastening a part to the conductor system. Figs. 4 and 5 show a modification, the former being a plan view, and the latter being a partial cross-section taken on line V—V, and Figs. 6 and 7 indicate in plan view the dimensions of the apertures in the carrier plate and of the connecting wires or strips fastened therein.
- For producing the carrier plate of Fig. 1 at first apertures are provided in this plate at the points 2, 3, 4 and 5, through which are passed the connecting wires 6 and 7 of a condenser 8 and the connecting wires 9 and 10 of a resistance 11. Figs. 2 and 3 show how the connecting

wires 6 and 7 of the condenser 8 and the connecting wires 9 and 10 of the resistance 11 are passed respectively through the apertures 2 and 3 and 4 and 5 provided in the carrier plate 1. After the parts have been mounted on the carrier plate, the conductor system, together with the enlarged terminal portions secured thereto for connecting the parts to this system, are produced in a mould by the die-casting process.

Fig. 1 shows in a plan view the conductors 12, 13, 14, and 15. In the form of construction of Fig. 2 the enlarged terminal portions 13a and 12a have been made at the same time with the conductor system. The conductor system and the points are of such a material and of such a constitution that the points of connection during the cooling down subsequent to die-casting enclose the extremities of the connecting wires 6 and 7 in a sufficient degree to hold fast these wires so as to be immovable. Consequently, in this case a special fastening of the connecting wires to the conductor system is not necessary. Moreover it appears from the figure that during die-casting the material of the conductor system has at least partly filled up the space between the connecting wires and the apertures in the carrier plate. The diameters of the various apertures in the carrier plate are chosen as small as possible with respect to the diameters of the connecting wires or strips, as otherwise it would be possible that during die-casting of the conductor system and of the points of connection the die-casting mass would flow to an unlimited degree through these openings.

In the form of construction of Fig. 3, the material of the conductor system has not the property of adhering to a sufficient extent to the connection leads. In this construction, therefore, an additional soldering operation is used, during which the connecting wires 9 and 10 are connected in the points 14a and 15a to the conductors 14 and 15 by the solder drops 16 and 17.

In contradistinction to the apparatus described above, in which the largest dimension of the parts extends in a direction parallel with the plate supporting them and in which consequently a comparatively large plate is necessary for providing the various parts, the advantage is obtained that the supporting plate may be much smaller, as a result of which the electric apparatus comprising the supporting plate may also be small. If, according to the invention, the parts are secured to the conductor system through their junction wires or connecting strips the advantage is secured that the supporting plate may serve as a mounting templet for the various parts, so that the mounting of the various parts in the mould described above and in the prior application, which takes a comparatively long time, can be dispensed with.

Generally the parts to be secured to the conductor system have their largest dimension in the direction of the connecting line between the points where the junction wires emerge from the parts. In this case this connecting line is consequently according to the invention, arranged at

least substantially normally to the plate supporting the parts. Of course, it is not necessary that all parts should be mounted in the manner referred to on the supporting plate. This depends on the available space, the course of the conductor system or the like.

An arrangement such as described above is shown in Figs. 4 and 5. The mounting plate 1 has mounted on it a condenser 22 and two resistances 23 and 24. The condenser 22 and the resistance 23 are arranged so that the connecting line of the points A and B or C, D at which the junction wires emerge from the parts extends normally to the plane of the plate 1. Thus it is ensured that the mounting plate 1 is occupied only by a very small part by these comparatively bulky parts. The resistance 24 is provided in such a manner that its main direction extends parallel with the plane of the plate 1. The various parts are passed with their junction wires through apertures in the plate 1 and secured to the conductor system which is made by die casting and whose various parts are designated by 25, 26, 27, 28, 29 and 30.

Fig. 6 shows the diameters of an aperture in the carrier plate and of the connecting wire with circular cross-section arranged in this aperture. The diameter of the connecting wire has a value d_1 and that of the aperture a value d_2 . In order to avoid that during producing of the conductor system and of the enlarged terminal portions die-casting material would pass in inadmissible quantities through the space between the internal wall of the aperture and the connecting wire, the diameters d_1 and d_2 of the apparatus according to the invention are so chosen that the distance between the wall of the aperture in the plate and the external side of the wire passed through this aperture is approximately at the most 0.2 mm.

Fig. 7 corresponds to the case that a connection strip with the cross dimensions h_1 and b_1 is passed through an aperture in the form of a slit having the dimensions h_2 and b_2 . In this case also the various dimensions are so chosen that the distance between the walls of the aperture in the plate and the external side of the strip passed through this aperture is approximately at the most 0.2 mm.

What we claim is:

A wiring system for the component parts of radio apparatus comprising an insulating base plate having formed therein suitably spaced apertures, the terminal leads of the component parts adapted to be disposed within said plate apertures, and a plurality of wire conductors having enlarged terminal portions die-cast on only one of the surfaces of the base plate, said terminal portions being aligned with and surrounding the terminal leads to form a rigid union therewith, the component part leads and the base plate apertures being so dimensioned as to permit only partial penetration of the wire conductor material during the die-casting process.
